VAPORIZING AND IGNITING MEANS FOR HYDROCARBON-LAMPS.

953,748.

Specification of Letters Patent. Patented Apr. 5, 1910.

Application filed November 6, 1908. Serial No. 461,347.

To all whom it may concern:

Be it known that I, YASUKE KAWASAKI, a subject of the Emperor of Japan, residing at Vancouver, in the Province of British Columbia, Canada, have invented a new and useful Improvement in Vaporizing and Igniting Means for Hydrocarbon-Lamps, of which the following is a specification.

This invention relates to a means for initially vaporizing and for igniting a hydro-carbon lamp of that class exemplified in the Gillett lamp, and my improvement is directed to the provision of a simple and convenient means for the initial vaporization and ignition of the gas where the lamps are used in positions where ignition is inconvenient by the means at present used. I accomplish this by providing the vaporizing tube with a coil of wire through which an electric current may be passed that will heat the wire to redness or to such a degree that will vaporize the hydro-carbon, and in series with this coil immediately over the globe of the burner I furnish a short section of platinum or other wire which with the same current will be heated to incandescence or to a temperature that will ignite the mixed air and gas as it is delivered from the burner of the lamp. With this arrangement, a current being turned through the vaporizing coil and the igniting wire, and the fluid hydro-carbon admitted under pressure to the vaporizing tube, that hydro-carbon will be vaporized by the heat from the coil and passing through the Bunsen mixer will be delivered from the burner and coming in contact with the incandescent platinum wire will be ignited thereby. After which the electric current may be cut off and the vaporization allowed to proceed in the usual manner by the waste heat from the lamp.

The invention is particularly described in the following specification, and illustrated in the drawings by which it is accompanied, in which:

Figure 1 is a side elevation and part section of a lamp showing the application of my initial vaporizing and igniting device thereto, and Fig. 2, an enlarged detail of the vaporizing tube showing the application of the initial vaporizing and igniting coils thereto.

In these drawings 2 and 3 represent the hollow suspension frame of the lamp, through one of which, 2, the fluid hydro-carbon is delivered under pressure to the

vaporizing tube 4 in the usual manner. The Bunsen air mixer 5 is placed in the down-take 6 through which the mixed air and gas is delivered to the burner 7, in order to afford a greater area for vaporization, but this arrangement does not constitute a necessary part of the invention. The incandescent mantle, which is not shown in the drawing is inclosed by the globe 8 which is carried up closer to the vaporizing tube than is the usual practice, as with my vaporizing and igniting device there is no need to provide accommodation for the application of the alcohol torch which is commonly used to secure the initial vaporization and ignition.

To the vaporizing tube 4 is applied a coil 10 to which is conveyed a current from an external electric circuit 9, the wires, suitably insulated, passing to the vaporizing tube 75 down one of the suspension tubes 3 of the lamp. The wire of this coil 10 is of such material and so proportioned to the strength of the current used, that it will be heated to redness, or to a temperature sufficient to vaporize the hydro-carbon. The coil may be applied in any suitable manner, but is preferably coiled on the outside of the tube, a thin sheet 11 of mica being first applied to the tube to electrically insulate the wire of 85 the coil from the metal of the tube. The coil is then inclosed with an outer layer 12 of mica and an outer sheathing 13 of thin sheet metal is spirally wrapped to hold the mica in place and protect it from injury. 90 These mica layers though necessarily exaggerated in thickness in Fig. 2 of the drawing, need only be very thin so that they will not interfere to any material extent with the passage of the heat from the coil inward to 95 the tube during initial vaporization or with the passage of the heat of the lamp to normally vaporize the hydro-carbon.

The other end of the wire of the coil is brought through the insulation and is connected by wires 14 to the return wire of the circuit 9, a short length of fine platinum wire 17 being introduced about the mid-length of the vaporizing tube, which being in series with the coil 10 will be heated to 105 incandescence, or to an igniting heat by the passage of the current.

The wires 14 may be supported in any suitable manner from the vaporizing tube, as shown in the drawing these supports 15 are of twisted wire bent around bands 16 of mica or other similar material that will in-

sulate them from the sheathing 18. The igniting wire 17 is preferably placed above the vaporizing tube to remove it from the direct action of the hot gases rising from the lamp, while its position is such that the gas and air rising from the burner 7 will readily come in contact with it for purposes of ignition.

The fluid hydro-carbon is delivered under pressure to the lamp in the usual manner by a capillary tube, a stop-cock being provided in a convenient position and the current which may be furnished from an electric service where such is installed or from a battery, is controlled by a switch adjacent. The current being turned on the tube 4 is heated, and when the hydro-carbon is thereafter delivered to the tube it will be vaporized by the heat and taking its supply of atmospheric air at the Bunsen mixer 5 passes down the pipe 6 to the burner 7 and rising therefrom is ignited by the incandescent wire 17 which has become heated to the necessary temperature by the passage of the same current which has heated the coil 10. As soon as the lamp is lighted the current may be cut off from the coil and the vaporization of the hydro-carbon will be effected by the heat from the lamp in the usual manner. A simple and convenient means is thus provided for the initial vaporization and ignition of the lamp, the cost of which will be but trifling.

The coil is applied to the exterior of the tube as the action of the hydro-carbon gas at a high temperature might have an injurious effect on the metal in the coil and render it brittle; and though objection may be urged to the mica covering of the vaporizing tube as being likely to interfere with the transmission of heat through it, I have not found such to be the case as the mica covering is very thin and as previously pointed out I am enabled to bring the vaporizing tube closer to the globe.

I am aware that prior to my invention a platinum wire through which an electric current has been passed, has been used to effect the ignition of a lamp, but believe I have been the first to secure the vaporization and ignition of a gas by the combination of a heating and igniting coil in series for the purpose specified.

Having now particularly described my invention and the manner of its application and use, I hereby declare that what I claim as new and desire to be protected in by Letters Patent, is:

1. In a hydro-carbon lamp, the combination with a burner, a mixing tube, a vaporizing tube and means for supplying hydro-carbon thereto, of a wire cooperating with the vaporizing tube that will on the passage of an electric current through it be heated to a temperature that will vaporize the

hydro-carbon within the tube, and another wire in series with said first wire that will on passage of the same current be heated to a temperature that will ignite the hydro-carbon vapor from the lamp when mixed with atmospheric air. 70

2. The combination in a hydro-carbon lamp of the class described of a mixing tube, a vaporizing tube, a burner and means for supplying hydro-carbon, a coil of wire 75 cooperating with the vaporizing tube that will on passage of an electric current be heated to a temperature that will vaporize the hydro-carbon, and a second wire in series with said first wire and held in a position exposed to the gas and air arising from the burner, said second wire being of such resistance that on passage of the same electric current it will be heated to a temperature that will ignite the mixed gas and 80 air. 85

3. The combination in a hydro-carbon lamp, of a mixing tube, a vaporizing tube and a burner connected therewith, means for supplying a hydro-carbon through the vaporizing tube to the burner, an electric heating unit on the vaporizing tube for vaporizing the hydro-carbon within the tube, and an electric igniting unit supported on the same tube to ignite the vaporized 90 hydro-carbon and air from the burner. 95

4. The combination in a hydro-carbon lamp of a burner, a mixing tube and a vaporizing tube and means for passing hydro-carbon to the burner through the vaporizing and mixing tubes and passing air to the burner through the mixing tube, an electrical heating unit supported on the vaporizer tube and an electrical igniting unit supported over the burner and in electrical connection with the heating unit, said heating and said igniting units being of such resistance that on the passage of an electrical current the heating unit will vaporize the hydro-carbon within the tube and 100 the igniting unit will ignite the combined vaporized hydro-carbon and air from the burner. 105

5. The combination in a hydro-carbon lamp having a burner and a vaporizing tube 115 held over said burner in alignment therewith; of a heating coil wound on said vaporizing tube, an igniting wire also supported on said vaporizing tube and electrically connected with said heating coil, and means 120 for connecting said coil and said wire with a source of electric energy to simultaneously energize both the said igniting wire and said heating coil.

6. The combination in a hydro-carbon 125 lamp having a burner and a vaporizing tube supported thereover, of a heating coil wound around said vaporizing tube, an igniting wire supported on said vaporizing tube over the burner, and means for con- 130

necting said heating coil and said igniting wire in series to a source of electric energy.

7. In a hydro-carbon lamp, the combination with a burner, a mixing tube, a vaporizing tube and means for supplying hydro-carbon thereto, of a wire co-operating with the vaporizing tube that will on the passage of an electric current through it be heated to a temperature that will vaporize the hydro-carbon within the tube, and another wire in series with said first wire that will on passage of the same current be heated to a temperature that will ignite the hydro-carbon vapor from the lamp when mixed with atmospheric air, and means for supporting said vaporizing tube over said burner to be heated by the ignited hydro-carbon vapor.

8. A hydro-carbon lamp, having a mixing

tube, a vaporizing tube and a burner connected therewith, together with means for supplying a hydro-carbon through the vaporizing tube to the burner, an electric heating unit on the vaporizing tube for vaporizing the hydro-carbon within the tube, an electrical igniting unit supported on the vaporizing tube to ignite the vaporized hydro-carbon and air from the burner, and means for supporting said vaporizing tube over said burner to be heated by the ignited hydro-carbon vapor.

In testimony whereof I have signed my name to this specification in the presence of two subscribing witnesses,

YASUKE KAWASAKI.
